OUTLET CONTROL AND AGITATOR
FOR BINS

William J. Kilpatrick, Detroit, Mich.

Application July 29, 1950, Serial No. 176,663

6 Claims. (Cl. 222—181)

1

This invention relates to mechanisms controlling the flow of bulk material from bins, and particularly such mechanisms applied to kitchen canisters receiving flour, coffee, sugar, or the like.

An object of the invention is to control the outlet of a bin or hopper by a cam-operable closure having a spring-maintained non-flow position beneath such outlet and pivoted to be laterally cammed to clear the outlet.

Another object is to minimize requisite closure travel by providing a pair of closures meeting medially of the bin outlet to close the latter, such closures being interconnected by a spring biasing them toward their non-flow position and being jointly actuatable by a cam to shift them apart and clear of the outlet.

Another object is to control the bin outlet by a pair of closures as above described, and equip each closure with a pair of pivotal supporting arms and to coaxially pivot the arms on a common shaft.

Another object is to dispose said arms and cams for actuating the same in an exterior relation to the bin so that they will not interfere with a flow of material, nor suffer interference from such flow.

Another object is to provide a simple and novel means for fixing a cam on a shaft in operative relation to an arm pivoted for deflection by the cam.

Another object is to extend a rock shaft through a bin above an outlet at the bin bottom, to mount an agitator on the shaft within the bin, and to adapt the shaft to actuate a closure for the outlet, pivoted exteriorly of the bin.

These and various other objects are attained by the construction hereinafter described and illustrated in the accompanying drawings, wherein:

Fig. 1 is a top plan view of a bin equipped with my improved flow control means.

Fig. 2 is a longitudinal vertical sectional view of the same, taken on the line 2—2 of Fig. 1.

Fig. 3 is a cross sectional view taken on the line 3—3 of Fig. 1.

Fig. 4 is a front end view of the bin and control means.

Fig. 5 is a sectional detail on line 5—5 of Fig. 2 of a means for locking a cam on its shaft.

Fig. 6 is an exploded view of the parts appearing in Fig. 5.

Fig. 7 is a perspective view of an agitator for installation in the bin.

In these views, the reference character 1 designates a rectangular bin having an elongated

bottom outlet 2. The bin has opposed side walls 3 converging downwardly to form lateral margins of the outlet, and opposed walls 4 similarly converging toward the outlet ends. The bin is so fitted between front and rear parallel walls 5 and 6 of a canister as to form a pyramidal chambers 7 at front and rear of the bin. Underlying and controlling the outlet 2 is a pair of elongated closures 8, laterally abutting each other medially of the outlet, in their now-flow position. Each such closure is carried at its ends by a pair of upwardly extending front and rear arms 9 and 9a occupying the chambers 7, the front arms having lapped upper ends, and the same being true of the rear arms. Said upper ends are pivoted on a shaft 10 carried by the bin medially between its walls 3, such shaft having end portions occupying the chambers 7 and adjoining the walls 5 and 6, the latter thus preventing material longitudinal play of the shaft.

Spaced downwardly from the shaft 10 is a cam shaft 11 extending through the bin and chambers 7 and journaled in the walls 5 and 6, and bent forwardly of the wall 5 to form an operating crank 12. Fixed on the shaft 11 in each chamber 7 is a cam 13 having a pair of fingers 14 at opposite sides of such shaft and parallel therewith, such fingers being respectively above and below the shaft when the arms 9 and 9a occupy their normal vertical position. To accommodate said fingers and also the shaft 11 between adjoined arms, the latter are similarly formed with arcuate recesses 15 in their inner edges, as best appears in Fig. 4. Each cam 13 with its finger 14 is preferably a sheet metal stamping, and preferably the fingers are transversely curved to present convex faces to the arms, minimizing friction. Coiled springs 16 interconnecting corresponding ends of the closures 8 tend to maintain an abutting relation of the closures, in which relation they are jointly restrained from any material lateral play by flanges 17 upstanding from the relatively remote lateral margins of the closures and straddling the outlet portion of the bin. Said flanges also reduce the likelihood of any material escaping over the relatively remote margins of the closures, rather than between the latter, during opening or closing of the closures.

The cams 13 are fixed on their shaft 11 in a quite simple but secure manner. Thus each cam is formed with a slot 18 of keyhole form, whereof the circular end is proportioned to slidingly accommodate the shaft and the reduced end may

straddle the parallel bottoms of two kerfs 19 oppositely formed in the shaft. Thus the cam may be slid along the shaft until it registers with said kerfs and may then be slid transversely of the shaft to enter the margins of the reduced end of the slot 18 in the kerfs and so requiring the cam to rotate in unison with the shaft. A sheet metal clip 20 is correlated with each cam to prevent such shifting of the latter as would afford registration of the circular end of the slot 18 with the shaft. The clip has a slot 21 of a length to accommodate both fingers 14 and of a width to receive the shaft. When said clip embraces the two fingers, as in Fig. 5, the cam is locked from shifting lengthwise of its slot 18. The cams 13 are in such proximity to the walls 5 and 6 as to prevent material longitudinal shifting of the cam shaft. The arms 9 and 9a are sufficiently close to the walls 4 of the bin to prevent shifting of such arms lengthwise of either shaft. The clips 20 are retained by said arms in engagement with the fingers 14.

Fixed on the shaft 11 within the bin is an agitator 22 for loosening the contents of the bin concurrently with lateral swinging of the closures. The preferred agitator is formed of sheet metal apertured and bent to form three bars 22a, 22b, and 22c parallel to the cam shaft, the bar 22a being just above the outlet 2 and the other two bars being above and at opposite sides of said shaft. The illustrated means for securing the agitator to the shaft comprises two wires 23 welded to supporting arms for the bar 22a and having end portions set into transverse openings of the shaft.

The described mechanism is rendered inexpensive by employing sheet metal stampings for its major parts and by simplicity of its assembly. Simplicity of its operation is a further asset, a slight depression of the crank 12 sufficing to loosen the bin contents and space the closures apart to clear the outlet.

What I claim is:

1. In an outlet control for bins, the combination with a bin having an elongated bottom outlet, of an elongated closure for the outlet disposed beneath the bin, a pair of supporting arms respectively secured to the respective closure ends and upwardly extending from such ends in an exterior relation to the bin, means coaxially pivoting the upper ends of said arms to afford lateral swinging of the closure for positioning said closure alternatively below or laterally of the outlet, a spring urging the closure toward its position below the outlet and means subjecting the closure to such spring, a shaft extending through the bin, a pair of cams fixed on the shaft and effective on the arms through rotation of

the shaft to swing the closure to one side of the outlet, and an actuating element on one end of said shaft.

2. An outlet control for bins as set forth in claim 1, and said means coaxially pivoting the arms being a shaft extending through the bin.

3. In an outlet control for bins, as set forth in claim 1, a pair of walls between which the bin is disposed, such walls being transverse to said shaft and chambers being formed between said walls and the bin, and the upper ends of said arms being coaxially pivoted within such chambers.

4. In an outlet control for bins as set forth in claim 1, and an agitator carried by said shaft within the bin.

5. In an outlet control for bins, the combination with a bin having an elongated bottom outlet, of a pair of elongated closures for the outlet disposed beneath the bin and having edges mutually abutting substantially medially of the outlet, a pair of arms supporting each closure and upwardly extending from its ends in a straddling relation to the bin, means coaxially pivoting the upper ends of said arms to afford lateral swinging of the closures from their abutting relation to a spaced-apart relation affording a discharge from the outlet, a spring interconnecting the closures and urging them to their mutually abutting relation, and cam means effective on said arms to swing the closures apart.

6. In combination with a shaft formed with opposed kerfs whose bottoms are substantially parallel, of a cam having a slot of keyhole form, such slot consequently having a circular end and a reduced opposite end, its circular end being adapted to slidably receive the shaft and its reduced end being adapted to straddle the bottoms of the kerfs and thereby resist rotation of the cam on the shaft, the cam having a pair of camming fingers in similar parallelism with and at opposite sides of the shaft, and a clip having a slot receiving the shaft and also receiving said fingers and thereby preventing shifting of the cam transversely of the shaft in a direction to release it from said kerfs.

WILLIAM J. KILPATRICK.
